UNITED STATES PATENT OFFICE.

WILLIAM HUGHES LOWELL AND MAX THEODORE WINTSCH, OF LANCASTER,
PENNSYLVANIA.

TRAIN-STOP.

1,301,468.

Specification of Letters Patent. Patented Apr. 22, 1919.

Original application filed January 24, 1918, Serial No. 213,521. Divided and this application filed August 16, 1918. Serial No. 250,164.

To all whom it may concern:

Be it known that we, WILLIAM H. LOWELL, a citizen of the United States, and MAX T. WINTSCH, a citizen of Switzerland, who has 5 declared his intention of becoming a citizen of the United States, both residing at Lancaster, in the county of Lancaster and State of Pennsylvania, have invented a new and Improved Train-Stop, of which the following is a description.

The present application is a division of an application for United States Patent filed by us January 24th, 1918, Serial No. 213,521, relating to a train stop of the automatic 15 type embodying a contrivance on the engine operable indirectly and controlled by electro-magnetic track devices.

The present invention relates particularly to the electro-magnetic controlling devices, 20 the nature and advantages of which will appear as the description proceeds.

In the accompanying drawings, forming part of the application, similar characters of reference indicate corresponding parts in 25 all the views.

Figure 1 is a diagram of the apparatus embodying our invention;

Fig. 2 is a side elevation of a slide device that may be operated by shoes included in 30 our invention and disposed along the track;

Fig. 3 is a section through the housing accommodating the electro-magnets for operating the shoes, the section being taken approximately on the line 3—3, Fig. 4;

Fig. 4 is a vertical section on the line 4—4, Fig. 3;

Fig. 5 is a plan view of the revoluble switch or commutator operable from the semaphore;

Fig. 6 is a transverse section on the line 6—6, Fig. 5.

Referring to the drawings, 13, 13' are shoes supported along side the railway tracks by rods 14 which are connected to 45 cores 15 of corresponding electro-magnets 16.

By means of these rods the shoes are disposed in different vertical planes so as to be engaged by independent rolling members.

The electro-magnets are mounted in a suitable casing 17 which carries guiding rollers 50 18 for the rods 14 of the shoes. The electro-magnets of the same shoe are in series with a switch 19 in which a spring 20 normally tends to close the same. The movable contact of the switch 19 carries a roller 21 which 55 is operable by a cam 22 provided on a rod of the corresponding shoe with the electro-magnets of which the switch 19 is in series.

The movement of the core 15 is controlled by a corresponding secondary electromagnet 60 23 which is in parallel with the corresponding main electromagnets 16. The secondary electromagnet controls a latch 24 which, when attracted by the electromagnet 23 will release a lug 25 and, therefore, allow the 65 main electromagnet to raise the shoe. The movement of the core upwardly operates the corresponding switch 19 and cuts off the current to the main electromagnets. The current passing through the secondary or latch 70 electromagnet causes said latch to engage a spring-operable pawl 26 and prevents the dropping of the shoe.

The circuit of the latch electromagnets and the shoe electromagnets is controlled by a 75 commutator 27 which is operable by the movement of a semaphore arm 28 (see also Figs. 5 and 6). The commutator has a contact plate 29 which is always in contact with a member 30 in all positions of the commutator, the member 30 being connected to the main supply line 31. The commutator has also contact members 32 and 33, the member 32 being connected by a conductor 34 to the latch electromagnets and the shoe electromagnets which are to operate at the "caution" 80 position of the semaphore. The contact 33 is connected by a conductor 35 to the latch magnets and electromagnets of the other shoe, which is operable at the "danger" position of the semaphore. The electromagnets may be grounded or connected, as shown, to a return conductor 36.

Preferably the conductors 34 and 35 are provided with switches 37 and 38 respectively. These switches allow the operation 90 95

of the shoes independently of the operation of the semaphore, as, for example, in cases where work is being done on the track within the block. These switches will be 5 located a distance past the road apparatus in the direction of traffic.

It is to be observed from a comparison of Figs. 3 and 4 that the shoes 13 are relatively positioned for each to engage a roller 39, it 10 being understood that said rollers traverse paths corresponding with the respective shoes 13.

When the semaphore is indicating "clear", the commutator brings the plate 29 into contact with all three members 30, 32 and 33. 15 In consequence the electromagnets 23 are maintained energized during that position of the semaphore. If the semaphore arm is moved to "danger", for example, that is, in 20 the position shown in full lines in Fig. 1, the circuit through the member 33 to the corresponding latch solenoid 23 will be broken; in consequence, the latch 24 will disengage the spring-actuated pawl 26 and allow the 25 corresponding shoe 13 to drop and, therefore, bring it into the path of the corresponding roller 39 of the locomotive. The tripping of the shoe closes the corresponding switch 19.

30 As the semaphore is moved to the "clear" position, the circuit will close, not only to the latch magnet 23, but also to the solenoid 16 through the corresponding switch 19. The latch magnet will disengage the latch 35 from the lug 25 and the energized electromagnet 16 will pull the shoe up and thereby bring the spring-actuated pawl 26 into engagement with the latch. The upward movement of the shoe throws the switch 19 40 open and thereby cuts off the supply of current to the electromagnet 16.

We would state in conclusion that while the illustrated example constitutes a practical embodiment of our invention, we do not 45 limit ourselves strictly to the mechanical details herein illustrated, since manifestly the same can be considerably varied without departure from the spirit of the invention as defined in the appended claims.

50 Having thus described our invention, we claim as new, and desire to secure by Letters Patent:

1. In a train stop, a gravitationally-operable shoe adapted to be disposed alongside 55 a railway track, electromagnetic means for raising the shoe against gravity, second electromagnetic means for engaging the shoe in the raised position, a normally-closed circuit for said second electromagnetic means, a switch in said circuit, a movable railway signal for operating said switch, said first 60 mentioned electromagnetic means being in shunt with the second-mentioned electromagnetic means, a switch in said shunt,

means tending to maintain said switch closed, 65 and means for opening said switch when the shoe is in the raised position.

2. In a train stop, a gravitationally-operable shoe adapted to be disposed alongside a railway track, electromagnetic means for engaging the shoe in the raised position, a normally closed circuit to said electromagnetic means whereby the same is maintained in operative engagement with the shoe in the raised position, a switch in the circuit, a 70 railway signal adapted to operate the switch to open or close the same to said electromagnetic means and whereby said shoe is allowed to drop when the circuit is broken, electromagnetic means for raising the shoe, said 75 second electromagnetic means being in shunt with the first, a switch in the shunt, means for closing the switch when the shoe is allowed to drop, and means for opening the switch when the shoe is raised by the second 80 electromagnetic.

3. In a train stop, a gravitationally-operable shoe disposed alongside of a track, a latch for engaging the shoe in the raised position, an electromagnet for retaining the 90 latch in engagement with the shoe in the raised position, a normally closed circuit to said electromagnet, a switch in said circuit, a semaphore signal for operating the switch whereby the circuit may be broken to release 95 the latch and allow the shoe to drop, an electromagnet for raising the shoe against gravity adapted to be in shunt with the latch electromagnet, and a switch in the shunt adapted to be open when the shoe is in raised position 100 and closed when the shoe is in lowered position, said switch operable by the semaphore arm adapted to close the circuit to the latch electromagnet and to the shunt whereby said latch is brought into the position to engage 105 the shoe when the same is raised by the second mentioned electromagnet.

4. In a train stop, a gravitationally-operable shoe, a latch, a spring-actuated pawl associated with the shoe and adapted to engage the latch when the shoe is in the raised position, an electromagnet for the latch to maintain the same in engagement with the pawl, a normally-closed circuit for said electromagnet, a switch in said circuit operable 110 by a railway signal to make and break the circuit to said electromagnet, said latch being adapted to release the pawl when the circuit is broken, whereby the shoe is allowed to drop, a second electromagnet for raising 115 the shoe against gravity in shunt with the first electromagnet, a switch in the shunt, means tending normally to close the switch, and a cam associated with the shoe and adapted to maintain said switch open when 120 the shoe is in the raised position.

5. In a train stop, a pair of gravitationally-operable shoes, electromagnetic means

for each of the shoes adapted to engage the shoe in the raised position, a normally closed circuit to each of the electromagnet means, a double switch in said closed circuit oper-
5 able by a railway signal and whereby either of the circuits may be broken and, therefore, either of the shoes allowed to drop, an elec-
tromagnet for raising each shoe in shunt

with the electromagnetic means of the cor-
responding shoe, and a switch in each shunt 10
adapted to be open when the shoe is in raised
position and closed when the shoe is in the
lowered position.

WILLIAM HUGHES LOWELL.
MAX THEODORE WINTSCH.
